CLAIM

The ornamental design for a shaker bottle lid as shown and described.

DESCRIPTION

FIG. 1 is a top front left perspective view of the shaker bottle lid showing the design;

FIG. 2 is a top front right perspective view thereof;

FIG. 3 is a top plan view thereof;

FIG. 4 is a front elevation view thereof;

FIG. 5 is a right elevation view thereof;

FIG. 6 is a left elevation view thereof; and,

FIG. 7 is a rear elevation view thereof.

The broken lines depict portions of the shaker bottle lid that form no part of the claimed design. The surface shading represents surface contours.
